UNITED STATES PATENT OFFICE.

CHARLES MORRIS HOLMES, OF JACKSONVILLE, FLORIDA.

DETACHABLE CORD SENDING-MACHINE CUT-IN.

1,252,570.

Specification of Letters Patent.

Patented Jan. 8, 1918.

Application filed August 18, 1916. Serial No. 115,598.

To all whom it may concern:

Be it known that I, CHARLES M. HOLMES, a citizen of the United States, and a resident of Jacksonville, in the county of Duval 5 and State of Florida, have invented a new and Improved Detachable Cord Sending-Machine Cut-In, of which the following is a full, clear, and exact description.

This invention relates to telegraphy, and 10 deals particularly with means for connecting a transmitting machine, such as a "vibroplex", with the main line through the sending key.

The invention has for its general objects 15 to equip a transmitting machine with a novel connecting means, whereby messages can be transmitted over one or more circuits without the use of other mechanical means, such as switch board connections or repeaters, this being accomplished by a split socket taking the place of the usual binding post, and a split plug adapted to be inserted in the socket and having its separate parts connected with the wires of a cord conductor 20 that leads to the terminals of the sending key, and by the use of two of such sockets, plugs and cord conductors, a transmitting machine can be connected with main line circuits leading to different and remotely 25 situated points, so that a message can be transmitted simultaneously in one operation to such points. These results can be accomplished without disturbing the normal condition of the two independent circuits.

30 With such objects in view, and others which will appear as the description proceeds, the invention comprises various novel features of construction and arrangement of parts which will be set forth with particularity in the following description and claims appended hereto.

35 In the accompanying drawing, which illustrates one embodiment of the invention and wherein similar characters of reference 40 indicate corresponding parts in all the views,

Figure 1 is a plan view of a transmitting machine with the circuits shown diagrammatically;

45 Fig. 2 is a detail sectional view on the line 2-2, Fig. 1, with the split plug removed from the socket;

Fig. 3 is a modified form of socket; and

50 Fig. 4 is a detail sectional view on the line 4-4, Fig. 2.

Referring to the drawing, A designates a transmitter for telegraph service, the machine being of that type known as a "vibroplex". Instead of the usual binding posts a split socket B is employed for connecting 60 the transmitter with the main line, the socket being divided into two parts 1 and 2 forming the terminals of the transmitter. The part 1 is grounded on the metallic base plate 3 of the transmitter, while the part 65 2 is insulated therefrom and connected with the contact make-and-break means of the transmitter. A plug C is adapted to be inserted in the socket B, this plug being divided longitudinally into two parts 4 and 70 5, which parts are separated from each other by a strip of insulation 6. The metal parts 4 and 5 are mounted in a ring or bushing 7 of insulation, and they are connected with the conductors 8 and 9 of a flexible cord 10. 75 This cord 10 leads to a sending key S of a main line, and it may be connected with the terminals of such key in any suitable manner. To connect the vibroplex with the sending key or disconnect it, it is merely 80 necessary to insert or remove the plug into or from the socket B. In transmitting machines manufactured with the improvement, the parts of the socket are set into an opening 11 in the base plate 1, there being a 85 fiber sleeve 12 inserted in the opening to fit around the socket-forming parts 1 and 2. For machines already in use, the socket-forming parts 1^a and 2^a may be fastened to the base plate by bolts 13 and 14 which are 90 inserted in the holes provided in the base plate 3^a for the usual binding posts. This construction is shown in Fig. 3, and it will be observed that one of the socket parts is 95 insulated from the base plate of the transmitting machine while the other is grounded thereon.

In Fig. 1 the transmitter is shown equipped with two terminal-forming split sockets B, and there are two plugs C and 100 cords 10 leading to the sending keys S. These keys are connected with separate main lines or independent circuits c and c' leading to distant stations. For instance, if it is assumed that the transmitter A is at 105 Jacksonville, Florida, the line c extends to a receiving station R at Tampa, Florida, and the circuit c' leads to a receiving station R' at Savannah, Georgia. By this arrangement the machine A becomes a double trans- 110

mitter and a message can be sent to both Savannah and Tampa by one operation of the machine A. This greatly simplifies and expedites the transmission of messages and 5 does away with the aid of switch board connections or of repeaters connected to the circuits, and furthermore, the detachable cord cut-in means enables the transmitter to be easily and quickly detached from the sending 10 keys, whereby the latter can be used for the transmission of messages in the ordinary way. The plug and socket connectors insure firm electrical connections between the transmitter and keys, and the connections 15 can be easily and quickly broken or made whenever desired.

From the foregoing description taken in connection with the accompanying drawings, the advantages of the construction and 20 method of operation will be readily understood by those skilled in the art to which the invention appertains and while I have described the principle of operation, together with the apparatus which I now consider 25 to be the best embodiment thereof, I desire to have it understood that the apparatus shown is merely illustrative and that

such changes may be made when desired as fall within the scope of the appended claims.

Having thus described my invention, I 30 claim as new and desire to secure by Letters Patent:

1. The combination of a vibroplex transmitter, a main line in two sections extending in opposite directions from the transmitter, 35 distance stations connected with the sections of the line, sending means connected with the sections of the line independently of the vibroplex transmitter, a cord conductor adapted to be connected in circuit with each 40 section of the main line, a two-contact plug connected with the wires of each cord conductor, and terminal sockets on the vibroplex transmitter for receiving said plugs.

2. The combination of a main line, a vibroplex transmitter, sending keys connected with the main line, a switch for shunting each key, a cord conductor having its wires connected in shunt with each switch, a two-contact plug connected with the wires of each cord conductor, and terminal sockets on the vibroplex transmitter for receiving the said plugs. 45 50

CHARLES MORRIS HOLMES.
